The invention relates to curtains or the like and it has particular relation to Venetian blinds. The ordinary type of Venetian blind comprises a series of slats disposed between spaced pairs of fabric strips or ribbons and these strips have interconnecting tabs disposed under each slat. While blinds of this character have been and are widely used, a common and serious objection to them is that the fabric strips become soiled or discolored and as a result the blind presents an unsightly appearance. It is exceedingly difficult to clean the strips since they are fastened to the structure and it is impossible to remove them for dry or other similar cleaning. Usually an attempt to clean them while in place leaves telltale discoloration or marks and often the strips have a worse appearance than they had before cleaning.

One object of the present invention is to provide a Venetian blind having an improved type of ribbon and slat supporting structure which will avoid the objections previously noted with respect to the fabric strips.

Another object of the present invention is to provide a Venetian blind which is more easily maintained in a clean condition and which has an improved appearance as compared to structures heretofore used.

Other objects of the invention will become apparent from the following specification, from the drawings relating thereto, and from the claims hereinafter set forth.

For a better understanding of the invention reference may be had to the drawings wherein:

Fig. 1 is an elevational view of a window having a Venetian blind constructed according to one form of the invention;

Fig. 2 is a cross-sectional view on a larger scale showing the arrangement of ribbons and slats.

Fig. 3 is a detailed view partly in cross section illustrating a modified form of the invention;

Fig. 4 is a detailed view illustrating a modified form of the invention; and,

Fig. 5 is an enlarged, sectional view taken substantially along line 5-5 of Fig. 1, illustrating the type of ribbon employed according to one form of the invention.

Referring to Figs. 1 and 2, the Venetian blind illustrated may provide an upper cross member or similar structure 10 and a lower cross member 11 constituting the upper and lower ends of the blind. In the design illustrated, three pairs of ribbons 12, 13 and 14 are connected to the cross members 10 and 11, and each of these pairs, as seen in Fig. 2, comprises ribbons 16 and 17.

The slats are indicated at 18 and each slat is supported on each pair of ribbons by a connecting element 20 comprising a bar or rod having ball shaped ends 21 and 22.

One improvement according to the present invention resides principally in the construction of the ribbon employed and the co-operation between the ribbons and the slat supporting elements. As shown best by Fig. 5, each ribbon 10 comprises an intermediate woven fabric 24 which is coated on both sides with a rubber-like material, as indicated at 25 and 26, bonded to the fabric. Various synthetic rubbers, for instance, may be employed as coatings for the fabric and one material found particularly suitable is "Koraseal." Such rubber materials may be furnished in various colors and designs and it should be evident that ribbons so constructed may be easily cleaned especially as compared to the work involved in cleaning ordinary fabric ribbons now used widely on Venetian blinds. Ribbons such as employed in the present invention may not only be cleaned easily but will not become stained in cleaning such as often occurs in cleaning ordinary fabric ribbons.

The slat supporting elements 20 are connected to the ribbons by forming openings 28, as seen in Fig. 3, with the openings slightly smaller than the ball elements 21 and 22 so that the material must be stretched in order to allow the ball elements to pass through the openings. In assembling the connecting slat supporting elements and ribbons, it is only necessary to press the apertured portion of the ribbon over the ball element and in doing this, the material can readily be stretched sufficiently to allow the ball to pass through the opening and then the material returns to its non-stretched condition so as to prevent the ball elements from becoming released. The rubber material is particularly useful in this connection due to its elasticity.

In the construction shown by Fig. 3, the slat supporting elements are shown as comprising a flexible strip 30 having a buckle-like element 31 on each end which is provided with a ball 32. Such ball elements are assembled with the ribbons in the same manner as already described in connection with the ball elements 21 and 22. The connecting strips 30 may be constructed of the same material as that of which the ribbons are constructed, and hence, the connecting strips may be readily cleaned without staining.

It has been stated that the ribbons may be constructed of woven fabric coated on both sides by material such as indicated. Under certain cir-

VENETIAN BLIND

Ollie L. Herron, Chicago, Ill.

Application October 29, 1945, Serial No. 625,203

3 Claims. (Cl. 160—178)

1

The invention relates to curtains or the like and it has particular relation to Venetian blinds.

The ordinary type of Venetian blind comprises a series of slats disposed between spaced pairs of fabric strips or ribbons and these strips have interconnecting tabs disposed under each slat. While blinds of this character have been and are widely used, a common and serious objection to them is that the fabric strips become soiled or discolored and as a result the blind presents an unsightly appearance. It is exceedingly difficult to clean the strips since they are fastened to the structure and it is impossible to remove them for dry or other similar cleaning. Usually an attempt to clean them while in place leaves telltale discoloration or marks and often the strips have a worse appearance than they had before cleaning.

One object of the present invention is to provide a Venetian blind having an improved type of ribbon and slat supporting structure which will avoid the objections previously noted with respect to the fabric strips.

Another object of the present invention is to provide a Venetian blind which is more easily maintained in a clean condition and which has an improved appearance as compared to structures heretofore used.

Other objects of the invention will become apparent from the following specification, from the drawings relating thereto, and from the claims hereinafter set forth.

For a better understanding of the invention reference may be had to the drawings wherein:

Fig. 1 is an elevational view of a window having a Venetian blind constructed according to one form of the invention;

Fig. 2 is a cross-sectional view on a larger scale showing the arrangement of ribbons and slats.

Fig. 3 is a detailed view partly in cross section illustrating a modified form of the invention;

Fig. 4 is a detailed view illustrating a modified form of the invention; and,

Fig. 5 is an enlarged, sectional view taken substantially along line 5-5 of Fig. 1, illustrating the type of ribbon employed according to one form of the invention.

Referring to Figs. 1 and 2, the Venetian blind illustrated may provide an upper cross member or similar structure 10 and a lower cross member 11 constituting the upper and lower ends of the blind. In the design illustrated, three pairs of ribbons 12, 13 and 14 are connected to the cross members 10 and 11, and each of these pairs, as seen in Fig. 2, comprises ribbons 16 and 17.

cumstances, it may be found desirable to coat only one side of the woven fabric such as the outermost side and then again it may be desirable under certain circumstances to use a solid rubber material without having woven fabric reinforcement. Again the ribbons instead of having woven fabric may be formed with vertical extending cords or cord fabric which may be embedded within the rubber. With respect to the connecting rods 20, these may be formed from plastic, metal or other suitable material. Here again the material may be colored as desired during its manufacture.

In the form of the invention shown by Fig. 4, the ribbons have snap fastener elements 35 which are adapted to be connected to slat supporting elements indicated at 36. Such slat supporting elements may have downwardly turned ends 37 provided with co-operating fastener elements 38 which snap into engagement with the eyes or fastener elements 35 on the ribbons. Thus the connecting elements may be readily applied or removed.

The usual means of tilting the slats may be used in the blind although this is not shown except for the pull cords 39 and 40. Also the usual depending loop 41 may be provided for raising the lower cross element 11 and this raising means usually will include cords 42 extending downwardly through the slats as seen in Fig. 2. Ordinarily the cords 42 are only used between the two end pairs 12 and 14 of the ribbons.

Venetian blinds constructed according to the invention may be manufactured inexpensively and the parts may be easily and readily assembled. Furthermore, the slat supporting elements may be readily disconnected from the ribbons and cleaned or replaced. The ribbons and connecting elements are both constructed from material which may be readily cleaned without staining and furthermore, the material does not absorb water and therefore will dry readily so that the reassembly may be made without waiting for any drying period. The material employed also enables using various colors and color combinations so as to enhance the appearance of the blind and also the surface of the material may be formed with various designs for the same purpose.

Although more than one form of the invention has been illustrated and described in detail, it will be apparent to those skilled in the art that various modifications may be made without departing from the scope of the claims.

What is claimed is:

1. A Venetian blind comprising upper and lower

cross supporting members, a series of slats arranged one above the other, a pair of resiliently flexible vertically extending ribbons connected at their upper and lower ends to the cross members and extending downwardly at opposite sides of the slats and having openings therethrough at the edges of the respective slats, and means connecting the ribbons at each slat and extending under the slat and comprising an element having knobs at its ends projectable through said openings, said ribbons comprising a rubber material and the openings therein being smaller than the knobs, the material being elastically stretchable to facilitate movement of the knobs through the respective openings.

2. A Venetian blind comprising upper and lower cross supporting members, a series of slats arranged one above the other, a pair of resiliently flexible vertically extending ribbons connected at their upper and lower ends to the cross members and extending downwardly at opposite sides of the slats and having openings therethrough at the edges of the respective slats, and means connecting the ribbons at each slat and extending under the slat and comprising an element having knobs at its ends projectable through said openings, said ribbons comprising fabric coated with rubber material and the openings therein being smaller than the knobs, the material being elastically stretchable to facilitate movement of the knobs through the respective openings.

3. A ribbon for use in supporting the slats of a Venetian blind including slat supporting elements having knobs adapted for connecting said elements to said ribbon, said ribbon comprising a strip of elastically stretchable rubberized material having openings therein slightly smaller than said knobs, said ribbon being stretchable within the elastic limit of the material to increase the size of said openings so that said knobs may be passed therethrough.
